UNITED STATES PATENT OFFICE

2,400,268

CALENDAR

Donald L. Skene, Lockport, Ill.

Application September 29, 1943, Serial No. 504,247

2 Claims. (Cl. 40—107)

The present invention relates in general to improvements in devices for designating dates, and relates more specifically to various improvements in the construction and operation of calendars or the like.

A primary object of my invention is to provide a new and useful calendar which is extremely simple and compact in construction, and which is also highly efficient in use and flexible in its adaptations.

Some of the more specific objects of the present invention are as follows:

To provide an improved date indicating assemblage having maximum utility while occupying minimum space, and which can be built or disposed within various objects such as pencils, pen-holders, lamp-stands, ash-trays, and other relatively elongated tubular bodies.

To provide an improved date indicator sheet for quickly and accurately designating any date of a predetermined year as to specific day of the week and month.

To provide an improved elongated substantially tubular calendar assemblage which may be quickly and conveniently adjusted to definitely indicate any desired date.

To provide an improved calendar date sheet which may be produced at minimum cost, and wherein all days and months of each succeeding year are displayed on a single page of relatively small size, thereby avoiding necessity of tearing off monthly date sheets and thus wasting paper.

To provide an improved holder for date indicating sheets which can be reproduced in various shapes and sizes, and which may moreover be conveniently manipulated to indicate the dates and for replacement of the yearly date sheets.

These and other specific objects and advantages of my invention will be apparent from the following detailed description.

A clear conception of the several features constituting the present improvement, and of the mode of constructing and of manipulating a calendar built in accordance with the invention, may be had by referring to the drawing accompanying and forming a part of this specification wherein like reference characters designate the same or similar parts in the various views.

Fig. 1 is a plan view of one of my improved date indicator sheets for the year 1943;

Fig. 2 is a side view of the same indicator sheet rolled into tubular form;

Fig. 3 is a part sectional side elevation of one type of assembled calendar having the indicator sheet of Figs. 1 and 2 disposed therein and the

indicating slide set to designate the date Tuesday, August 17, 1943;

Fig. 4 is a transverse horizontal section through the tube and indicator sheet of the assemblage shown in Fig. 3, looking downwardly;

Fig. 5 is a transverse horizontal section through the indicating slide of the same assemblage; and

Fig. 6 is a central vertical section through the upper tapered indicator sheet retainer and manipulator.

While the invention has been illustrated and described herein as being embodied in a simple tubular standard provided with a plane support or base, it is not my desire or intent to thereby unnecessarily restrict the scope or adaptations of the improved features, which are obviously susceptible of embodiment in various objects and devices, such as pencils, pen-holders, lamp-stands, ornamental ash-trays, columns of various types, and many others.

Referring to the drawings, the improved calendar assemblage shown therein by way of illustration, comprises in general a support or base 8, a tubular casing 9 fixedly mounted in upright position upon the base 8 and having an elongated slot 10 therein; a circular tapered lower centering retainer block 11 rotatably secured to the base 8 centrally of the casing 9 by means of a screw 12 or the like; a circular tapered upper centering retainer and manipulating block 13 rotatably confined within the upper open end of the casing 9; a date indicator insert or sheet 14 having thereon successive rows or parallel columns of relatively staggered date indicating numerals 15, said insert being adapted to be rolled into tubular formation and confined within the casing 9 in frictional engagement with the tapers of the blocks 11, 13; and a date indicator frame or slide 16 coaxing with and movable along the casing slot 10.

The support or base 8 may be of any desired size or shape. The tubular casing 9 may likewise be formed of any suitable sheet-material, and may have either circular or any other cross-sectional shape, and when the calendar is used as a novelty or for advertising purposes, this casing 9 may be decorated or provided with advertising matter. The tubular sheet retainer blocks 11, 13 may be constructed of wood, plastic or other material, and may be formed with central through openings 51 as shown in Fig. 6, in order to provide passages for wires or mechanical lead feeding mechanisms, and in such cases the lower pivot screw 12 should also be made hollow. The upper block 13 may also be provided with a manipulating flange 18 for effecting convenient rotation thereof. The

indicator frame or slide 16 has a central opening 19 therein as shown in Figs. 3 and 5, and is provided with curved spring fingers 20 coacting with the interior of the casing 9 and with the exterior of the tubular sheet 14, to further aid in centering the tubular sheet 14 within the casing 9.

The specific formation and construction of the date indicating insert or sheet 14 is an important feature of the present invention, and as shown in Figs. 1 and 2, this sheet bears twelve vertical rows or columns of numbers 15, each row representing the days of a month, and the successive rows being divided by transverse areas 21 into weekly periods. The day designating numerals 15 of the successive months are staggered relative to each other and so positioned that they will fall on the proper day of the week, and the casing 9 may also be provided with letters 22 designating the successive days of the week, see Fig. 3. One simple mode of producing the sheets 14 is to print the numbers 15 appearing in the transverse areas 21 in red or some other distinct color which is different from that used in the remaining numerals, and the areas 21 may be used to designate Sundays. Holidays not falling on Sundays, may also be printed in distinctive colors, and as previously indicated, the insert or sheet 14 shown in the drawing is properly produced for the year 1943. One edge of each date sheet 14 may be provided with adhesive in order to permit the sheet 14 to be secured in cylindrical shape as illustrated in Fig. 2, and when thus assembled, the tubular sheet 14 should be adapted to snugly frictionally embrace the oppositely tapered portions of the rotary retainer blocks 11, 13 as shown in Fig. 3.

When the date indicator sheet 14 has been properly produced and applied to the blocks 11, 13 within the tubular casing 9 as depicted in Figs. 3 and 4, the flange 18 of the upper retainer and manipulating block 13, may be utilized to place any one of the twelve vertical rows of dates in alinement with the elongated slot 10 of the casing, by merely rotating the upper block 13. The blocks 11, 13 and the tubular sheet 14 will then be frictionally retained in adjusted position, and as shown in Fig. 3 the month of August has been positioned in alinement with the casing slot 10. The areas 21 will then be positioned in horizontal alinement with the corresponding week day letters 22 on the casing 9, and the slide 16 may thereafter be adjusted vertically along the slot 10 so as to display any selected date and its week day designation, such as Tuesday, August 17th, within a frame. The slide 16 may obviously be lowered daily by one spacing of the superimposed numerals, thus giving a correct indication of the successive dates.

From the foregoing detailed description it will be apparent that my present invention provides a calendar or date indicator which is extremely simple and compact in construction, and which is furthermore efficient and accurate in use and very flexible in its adaptations. The improved calendar assemblage may be incorporated in many different objects of various sizes and shapes, and the improved inserts or date sheets can be printed or otherwise produced at low cost.

The new device is also quickly and conveniently manipulable to correctly designate any desired date, and the shape of the casing 9, slide 16 and other parts may obviously be modified throughout a considerable range. The improved assemblages may be produced in quantity at relatively low cost, and are therefore well suited for novelty and advertising purposes besides having extreme utility.

10 It should be understood that it is not desired to limit this invention to the exact details of construction or to the precise mode of use and operation, herein shown and described, for various modifications within the scope of the claims may occur to persons skilled in the art.

I claim:

1. In a calendar, a tubular casing having an elongated rectilinear slot extending throughout the major length of the casing and provided with closed opposite ends, a tubular cylindrical calendar insert disposed concentrically within said casing and having parallel staggered monthly date columns successively alineable with said slot when said casing and insert are relatively rotated, said casing having a series of fixed week day designations disposed along a side of said slot, an indicating frame having portions slidably confined within said slot, said portions coacting with the interior of said casing and with the exterior of said insert to aid in centering the latter within the casing, and said frame being provided with a sight opening formed to cooperate with said casing and said insert to visibly expose only one selected week-day designation and the corresponding month date while the frame conceals the adjoining designations and dates from view, and a manually rotatable centering element for said insert frictionally bound thereto and being journaled in said casing for rotation of the insert.

2. In a calendar, a tubular casing having an elongated rectilinear slot extending throughout the major length of the casing and provided with closed opposite ends, a tubular cylindrical calendar insert disposed concentrically within said casing and having parallel staggered monthly date columns successively alineable with said slot when said casing and insert are relatively rotated, said casing having a series of fixed week day designations disposed along a side of said slot, an indicating frame having portions slidably confined within said slot, said portions coacting with the interior of said casing and with the exterior of said insert to aid in centering the latter within the casing, and said frame being provided with a sight opening formed to cooperate with said casing and said insert to visibly expose only one selected week day designation and the corresponding month date while the frame conceals the adjoining designations and dates from view, a manually rotatable tapered centering element for said insert frictionally bound to one end thereof and being journaled in said casing for rotation of the insert, and another centering element for said insert coacting with the opposite end thereof in axial alinement with said manually rotatable element.

DONALD L. SKENE.
